SHOT PATTERN CONTROL MUZZLE ATTACHMENT FOR FIREARMS

Edward Baden Powell, Pasadena, Calif., assignor of one-half to Frank A. Pachmayr, Los Angeles, Calif.

Application October 18, 1948, Serial No. 149,168

Term of patent 14 years

(Cl. D30—1)

To all whom it may concern:

Be it known that I, Edward Baden Powell, a citizen of the United States, residing at Pasadena, California, in the county of Los Angeles and State of California, have invented a new, original, and ornamental Design for Shot Pattern Control Muzzle Attachment for Firearms, of which the following is a specification, reference being had to the accompanying drawing, forming a part hereof, and in which:

Fig. 1 is a plan view of a shot pattern control muzzle attachment for firearms embodying my new design; and

Fig. 2 is a side view of Fig. 1.

The present design is characterized by rows of square openings which are uniformly spaced and in opposed relation, the said rows of openings being arranged in groups of three rows each and having said groups in spaced relation, all as shown.

I claim:

The ornamental design for a shot pattern control muzzle attachment for firearms, substantially as shown, and described.

EDWARD BADEN POWELL.
